US0D1009674S

(12) **United States Design Patent** (10) Patent No.: **US D1,009,674 S**
(45) Date of Patent: ** Jan. 2, 2024

(54) **COMBINED BRACELET AND HAND SANITIZER DISPENSER**

(71) Applicant: **Usman Rehan**, Richmond, TX (US)

(72) Inventor: **Usman Rehan**, Richmond, TX (US)

(**) Term: **15 Years**

(21) Appl. No.: **29/723,160**

(22) Filed: **Feb. 5, 2020**

(51) LOC (14) Cl. **11-01**

(52) U.S. Cl.

USPC **D11/2**

(58) **Field of Classification Search**
